UNIVERSALLY-ADJUSTABLE VISE FOR HOLDING WORK FOR GRINDING AND INSPECTION

Joseph I. Jalbert, Arcadia, Calif.

Filed Apr. 13, 1959, Ser. No. 55,477

Term of patent 14 years

(Cl. D54—13)

Des. 191,178

PAGE 2

FIG. 1 is a front elevational view of a universally-adjustable vise for holding work for grinding and inspection showing my new design.

FIG. 2 is a top plan view thereof in a different position of adjustment.

FIG. 3 is an end elevational view of the vise as seen from the left side of FIG. 1 and drawn to a reduced scale.

FIG. 4 is an end elevational view as seen from the right side of FIG. 1 drawn to the scale of FIG. 3.

FIG. 5 is a similarly reduced rear elevational view with a portion broken away for convenience of illustration.

The dominant features of the design are shown in the drawing in full lines.

I claim:

The ornamental design for a universally-adjustable vise for holding work for grinding and inspection, substantially as shown and described.
